United States Patent Office

Des. 195,739
Patented July 23, 1963

195,739

BOTTLE

George W. Worthington, Castro Valley, Calif., assignor to Owens-Illinois Glass Company, Toledo, Ohio, a corporation of Ohio

Filed Mar. 4, 1963, Ser. No. 73,792

Term of patent 14 years

(Cl. D58—8)

—1—

FIG. 1 is a side elevational view of a bottle showing my new design; and

FIG. 2 is a top plan view of the bottle.

The sides not shown are the same as the side shown in elevation on FIG. 1.

I claim:

The ornamental design for a bottle, substantially as shown and described.
